FISH LURE

Ewell J. Harris, Rte. 3, Box 135A,
Adrian, Mich. 49221

Filed June 21, 1972, Ser. No. 264,790

Term of patent 14 years

Int. Cl. D22—05

U.S. Cl. D22—29

FIG. 1.

FIG. 5.

FIG. 2.

FIG. 6.

FIG. 3.

FIG. 7.

FIG. 4.

FIG. 8.

FIG. 1 is a top plan view of a fish lure embodying the present invention;

FIG. 2 is a side view of the fish lure shown in FIG. 1;

FIG. 3 is a bottom view of the fish lure shown in FIGS. 1 and 2;

FIG. 4 is a front view of the fish lure shown in FIGS. 1 through 3;

FIG. 5 is a top plan view of another fish lure embodying the present invention;

FIG. 6 is a side view of the fish lure shown in FIG. 5;

FIG. 7 is a bottom view of the fish lure shown in FIGS. 5 and 6; and

FIG. 8 is a front view of the fish lure shown in FIGS. 5 through 7.

I claim:

The ornamental design for a fish lure, substantially as shown and described.
